UNITED STATES PATENT OFFICE.

KARL F. KIRKMAN, OF ERIE, PENNSYLVANIA, ASSIGNEE TO AUTOMATIC PRESS FEEDER COMPANY, OF CHICAGO, ILLINOIS, A CORPORATION OF ILLINOIS.

PRINTING-PRESS.

1,077,282.

Specification of Letters Patent. Patented Nov. 4, 1913.

Original application filed January 19, 1909, Serial No. 473,171. Divided and this application filed October 1, 1909. Serial No. 530,512.

To all whom it may concern:

Be it known that I, KARL F. KIRKMAN, a citizen of the United States, formerly residing at Chicago, Cook county, Illinois, and 5 also at Rockford, Winnebago county, Illinois, but now residing at Erie, Erie county, Pennsylvania, have invented certain new and useful Improvements in Printing-Presses, of which the following is a specification, this application being divisional of 10 an application filed by me on January 19, 1909, Serial No. 473,171.

My invention relates to printing presses and the object thereof is to provide novel 15 and efficient automatic means for supplying sheets of paper from a pile of sheets to the printing mechanism of a press, my present invention representing an improvement upon the machine or attachment described 20 and claimed in my former application filed on January 20, 1908, Serial No. 411,677, and being a substitute for the paper supplying mechanism thereof, the means for presenting the paper to the printing form and delivering it from the machine as described in 25 said former application remaining substantially the same.

My invention may be incorporated in a new printing press as an integral part thereof, or may be built as an attachment to be applied to printing presses already in use, the same being particularly applicable to 30 presses of the Gordon type.

The various features of novelty and utility 35 in my invention will be apparent from the description hereinafter given.

In the drawings, Figure 1 is an elevation of one side of a portion of the well-known Gordon press showing my invention incorporated in an attachment applied thereto; 40 Fig. 2 a similar view but of the other side of such press; Fig. 3 a detail sectional view; Fig. 4 a plan view of the attachment; Fig. 5 a sectional elevation similar to Fig. 3 but on 45 a smaller scale and in addition showing some of the operating connections; and Figs. 6 and 7 a plan view of some of the operating shafts, cams and levers.

Referring to the present embodiment of 50 my invention as illustrated in the drawings, I have shown the same in the form of an attachment which is applied to and mounted upon the frame 1 of the well-known Gordon

printing press with the exception that the platen 2, instead of being movable as is usual, is blocked or in any other suitable way made immovable, the type bed 3 which carries the type or printing form remaining movable in the ordinary way. It will be understood, however, that the particular 55 type or style of printing press is immaterial and that my invention, as hereinbefore stated, may be built as an integral part of the printing press structure or as an attachment, but for the purposes of an understanding of my invention I will proceed to describe the same as herein illustrated and as the same is used in practice, that is as an attachment to a Gordon press modified 60 slightly in the manner stated. 70

My attachment is provided with a main frame 4 forming a support for the different working parts of the attachment and secured in any suitable manner to the printing press frame 1. At the upper end of this frame 75 4 I mount an endless conveyer comprising a pair of transverse rollers 5 and 6 and a suitable endless belt 7. By preference this belt is made continuous from side to side and as clearly shown in Fig. 3 the same 80 slides upon the upper surface of a support 8 located between said rollers along the top reach of the belt. This belt is adapted to receive and to slowly feed as required the pile of paper which is placed thereupon in 85 combed form and kept in that condition and fed by such belt. For the purpose of properly feeding the paper, the endless belt is moved as required, and in suitable manner, for instance, by means of the ratchet wheel 90 9 operatively connected with the front roller 6 and coöperating with the pawl 10 which is mounted upon the pawl carrier 11 whose oscillation and proper timing as to movement will be hereinafter described. The 95 front edge of the paper is stopped by means of a cross bar 12 having a series of rearwardly-extending fingers 13 which are formed separately or integral therewith and adapted to lie in grooves formed in the belt 100 by reason of the fact that the front roller 6 is itself provided with a series of circumferential grooves 6^a as clearly shown in Fig. 3. It will be understood that owing to the tension and pliable nature of the belt, the latter will assume the same surface character as.

the front roller 6. By this means the paper will be properly received and stopped by the fingers 13 and be prevented from following the belt, but on the contrary such fingers 5 will take off the front end of the sheets from the belt.

For the purpose of separating the top sheets one at a time from the pile of sheets a transverse roller 14, preferably corrugated and of suitable material, such as rubber, is provided. This roller is arranged to be oscillated in contact with the top sheet of paper first in one direction and then in the other and to be slightly raised during the time that such sheet is being pulled from the pile by the feed rolls hereinafter described. In one of said oscillations this roller 14 causes the paper to buckle and because of this function I will hereinafter refer to the same as the "buckling roller." This roller is journaled at its ends in bearings 15 and provided with the central shaft or axis 16. In practice this shaft is connected at one end with a bevel gear 17 adapted to mesh with a corresponding bevel gear 18 (Figs. 2 and 6) mounted on and driven by the vertical shaft 19 carrying at its lower end a similar bevel gear 20. This latter gear is adapted to mesh with a segmental bevel gear 21 to which is operatively connected an oscillating crank arm 22 driven by means of operating connections hereinafter described. In order to provide for a slight vertical movement of the buckling roller a sliding connection is provided between the shaft 19 and either one of its bevel gears in the present instance bevel gear 18. The buckling roller cooperates in the buckling operation with a normally fixed but adjustable transverse bar 23, 26 extending across the pile of sheets and in proximity to the top sheet thereof. The object of this roller is to cause the paper to buckle or move upwardly when the buckling roller is oscillated in a direction to move the top sheet rearwardly as to its front portion. In order to accommodate sheets of different thickness this roller 23 is adapted to be adjusted toward or away from the buckling roller. To this end and as a means for supporting such roller, the latter is rotatably mounted on a shaft 24 which is adjustably secured in longitudinal slots 25 formed in blocks 26 at each side of the machine, all as clearly indicated in Figs. 3 and 4. These blocks are carried by and extend forwardly from a cross frame comprising the cross bar 27, preferably having on its underside a supplemental bar or piece 28 of suitable material, such as wood, adapted to press directly upon the pile of sheets. Said frame also comprises upright portions 29 located at the ends thereof and connected by the cross-shaft 30. This shaft extends through and is guided by substantially vertical slots 31 in an upward extension of the at-

tachment frame 4 and the same, together with the entire cross frame, is held downwardly upon the paper with a yielding pressure by means of springs 32 arranged in said slots 31. These springs may be adjustable in tension in any suitable manner as by means of the adjusting screws 33. In the present instance the roller 23 is held in adjusted position by the bearing shaft 24 adjustable in the slots 25 and held in adjusted position by means of the clamping bolts 34, the ends of the blocks 26 being properly slotted as clearly shown in Fig. 3 to provide for such clamping. The cross bar 28 and the roller 23 are adapted to press upon the pile of sheets with a yielding pressure but arranged to be slightly withdrawn therefrom at the time when the top sheet after being buckled is being fed forwardly into the machine by the feed rolls in the manner hereinafter explained. To this end I provide a pair of oscillating levers 35 arranged at opposite sides of the machine as indicated in Figs. 5 and 6 with their rearward ends in contact with the underside of the vertically movable boxes or blocks 36 which slide in the slots 31 with the result that when said levers 35 are oscillated upwardly the cross bar 28 and roller 23 will be slightly raised against the tension of the springs 32. To afford proper movement to said levers, the latter are secured to the cross shaft 37, one of said levers, as shown in Figs. 4, 5 and 6, being connected by means of the link 38 to an oscillating bell crank 39 pivoted on the main frame 4. This bell-crank has a cam roller 39^a which is so arranged as to cooperate with a cam 39^b secured to the cross shaft 48, thereby giving the roller 14 a positive movement to and from the paper.

In front of the buckling roller is arranged a series of rearwardly extending fingers 42 whose rearward ends extend downwardly in contact with the top sheet of paper and whose forward ends are secured to or form a part of a transverse rod or shaft 41 having an oscillating movement. During the time when the buckling roller is moving in its clockwise direction (Fig. 3) for the purpose of moving the front end of the top sheet of paper so being acted upon has passed to the rear of these fingers, the latter are moved downwardly upon the second sheet of paper which will subsequently become the uppermost one, with the result that in the movement of the buckling roller in the opposite direction, the front edge of the top sheet will be directed and deflected by said fingers in an upward direction and free from the pile of paper. These fingers 42 are oscillated in proper time with the other mechanisms 105 110 115 120 125 130 135

in suitable manner and in the present instance the same are operated by means of an arm 40 secured to one end of shaft 41 and connected by means of a link 43 to one end 5 of a lever 44. This lever, which is pivoted at 45, is provided at its center with a cam roller 46 adapted to coöperate with and be actuated by a cam 47, secured to one of the main driving shafts 48^a of the machine.

10 In order to automatically keep a uniform depth of paper underneath the buckling roller, that is a uniform thickness of paper between the lower surface of such roller and the upper surface of the feed belt 7, I provide suitable means which, in the present instance, consists of mechanism controlled by the relative position of the buckling roller for actuating the feed belt. As shown, a vertical link 49 is connected at its upper 15 end with bell crank 39, Fig. 5, while its lower end is pivoted to the lever 50, the extreme end of which is connected by means of a link 51 to the outer end of the pawl carrier 11 hereinbefore described. When in 20 the feeding of the paper the buckling roller is lowered from its normal position, the link 49 is forced slightly downwardly, by reason of its connections with the bell crank 39 and link 38, with the result that the lever 50 is 25 slightly oscillated in a clockwise direction, (Fig. 5) so that a cam roller 52 is brought into the path of travel of the cam 53 secured to the driving shaft 48. When, in its rotation, this cam contacts the cam roller 52, 30 the pawl-carrier 11 is moved upward by reason of its connection with the lever 50 through the link 51 and the pawl 19 will be caused to engage a tooth or teeth as the case 35 may be on the ratchet 9 and move the feed belt forwardly in slight degree but sufficient 40 to move the pile of paper forwardly to provide the uniform depth of paper underneath the buckling roller. When the topmost sheet of paper is fed forwardly by the buckling roller and deflected upwardly by the fingers 42, the same will be directed between the two feed rolls 54 and 55, of which the former is positively driven as hereinafter 45 explained, and of which the latter is an idler, Figs. 3 and 4. From these feed rolls the sheet of paper passes between a second pair of feed rolls 56 and 57, the former being a positively driven roll and the latter an idler. This idler is spring-pressed to- 50 ward the feed rolls 56 by means of a spring 58, whose tension may be regulated by the adjusting screw 59. The paper is guided to the first set of feed rolls by fingers 42 and into the second set of feed rolls by means of 55 guides 60, Figs. 3 and 4. From the latter set of feed rolls the paper passes downwardly in an inclined direction between the carrying tapes 61, the paper being presented to a transfer frame and presented thereby 60

to the printing mechanism and subsequently 65 delivered from the machine in the same general manner as explained in my prior application aforesaid.

Referring to the driving connections for the parts described, the power is transmitted from the main power shaft 62 through the train of gears and pinions 63, 64, 65, 66, 67, 68, 69, thence through the shaft 48^a to the other side of the machine, gears 70 on said shaft, and through the train of gears 75 71 and 72 to shaft 73 on the outer end of which is secured the gear 74, thence to the train of gears 75, 76, 77, 78, and 79, and through the lower train of gears 80, 81, 82, 83 and 84. The gear 71 is secured to the 80 cross-shaft hereinbefore referred to and the same is provided at its outer end with a box cam 85 with which operates the roller 86 which is mounted upon the lower end of the link 87 whose upper end is pivotally connected to the crank arm 22 hereinbefore referred to. By means of this construction the buckling roller is given its oscillating movements hereinbefore described. The train of gears 74 to 79 drive the feed rolls 90 hereinbefore mentioned.

I claim:

1. In feeding mechanism for a printing press, the combination of an endless belt adapted to support a pile of sheets of paper, 95 rollers for said belt, one of which is circumferentially grooved to thereby form corresponding grooves in the belt passing thereover, and a series of fingers positioned in said grooves to take off the front end of 100 the sheets from the belt.

2. In feeding mechanism, for a printing press, the combination of an endless belt adapted to support a pile of sheets of paper, 105 rollers for said belt, one of which is circumferentially grooved to thereby form corresponding grooves in the belt passing thereover, and a stop bar arranged at the forward end of the belt and having a series of fingers positioned in said grooves to take 110 off the front end of the sheets from the belt.

3. In feeding mechanism for a printing press, the combination of a support for a pile of sheets of paper, an oscillating roller adapted to buckle the topmost sheet thereon, 115 movable bearing boxes for the roller, yielding pressure means for holding the boxes and roller toward the pile, a cross shaft 30, a cross frame suspended therefrom and having blocks 26 projecting forwardly, a pressure bar 23 mounted in said blocks, and a supplemental bar 28 upon the underside of the cross frame.

4. In feeding mechanism for a printing press, the combination of a support for a 125 pile of sheets of paper, an oscillating roller adapted to buckle the topmost sheet thereon, movable bearing boxes for the roller, yield-

ing pressure means for holding the boxes and roller toward the pile, a cross-shaft 30, bearing boxes for the shaft, yielding pressure means for acting on the latter boxes, a cross frame suspended from the cross-shaft, a pressure bar 23 mounted in said cross frame, and arms acting upon the boxes of

the roller and shaft for positively moving them away from the pile when the topmost sheet is being removed.

KARL F. KIRKMAN.
